CLAIM

The ornamental design for a removable lid with pump holder, substantially as shown and described.

DESCRIPTION

FIG. 1 is a top perspective view of a removable lid with pump holder in accordance with the present design.

FIG. 2 is a bottom perspective view of the removable lid with pump holder.

FIG. 3 is a left side view of the removable lid with pump holder.

FIG. 4 is a right side view of the removable lid with pump holder.

FIG. 5 is a front view of the removable lid with pump holder.

FIG. 6 is a back view of the removable lid with pump holder.

FIG. 7 is a top view of the removable lid with pump holder.

FIG. 8 is a bottom view of the removable lid with pump holder; and,

FIG. 9 is a perspective view of the removable lid with pump holder, shown in a position of use with exemplary environmental subject matter.

The broken lines shown for the purpose of illustrating exemplary environmental subject matter that forms no part of the claimed design.

1 Claim, 5 Drawing Sheets
